ANNEALING COVER

Albert N. Koch and Clyde C. Huffman, Detroit,
Mich., assignors to Steel Plate & Shape Cor-
poration, Detroit, Mich., a corporation of Dela-
ware

Application June 19, 1939, Serial No. 279,968

5 Claims. (CL 263—49)

This invention relates generally to annealing covers for metal members or pieces while they are being heat treated.

Heretofore the roof plates of annealing covers have had extensions that projected laterally over and beyond the upright side plates, consequently the hot gases from the tubes in the furnace shell proper could not pass up the side plates of the cover without interference with such extensions. 10 In fact, the flow of such gases was retarded so that they were in effect pocketed or trapped where the roof plates extended over the side plates. This in turn caused rapid deterioration of the cover and frequently caused the roof plates to burn out 15 completely at the juncture thereof with the side plates.

In the present instance, the objectionable construction referred to has been dispensed with entirely and a better and more efficient structure 20 has been provided. Moreover, the cover has been otherwise strengthened to give it rigidity and to prevent the same from collapsing while being handled or while in use.

In the accompanying drawing:

25 Figure 1 is a fragmentary side elevation of a cover embodying our invention;

Figure 2 is a fragmentary end elevation thereof;

Figure 3 is a fragmentary top plan view thereof;

30 on the line 4—4 of Figure 1;

Figure 5 is a sectional view taken substantially on the line 5—5 of Figure 2;

Figure 6 is a sectional view taken substantially on the line 6—6 of Figure 3;

35 Figures 7, 8 and 9, respectively, are fragmentary vertical sectional views of alternative rib constructions.

Referring now to the drawing, A, B, C and D, respectively, are the upright wall members, and 40 E is the roof member of an annealing cover embodying our invention.

As shown, the upright wall members are formed of sheet metal and have straight end portions 10 and corrugated intermediate portions 11. Preferably these upright wall members are arranged in the form of a hollow rectangle with the corrugations 11 extending vertically and with the straight end portions 10 of adjacent wall members abutting and welded together so that an integral unit is provided. As illustrated in Figures 1 and 2, the side walls A and B are higher than the end walls C and D.

The roof member E is preferably arched transversely and comprises a sheet of metal provided 55 at opposite sides thereof with straight edge por-

tions 12 and intermediate wavy edge portions 13. As illustrated in Figures 1 and 3, these straight edge portions 12 are at the front and rear ends of the roof member and abut and are welded to the straight end portions 10 of the upright wall members A and B, while the wavy edge portions 13 conform in shape and are welded to the inner faces of the corrugations 11 of the upright wall members A and B just below the upper ends of the latter.

10 F are reinforcing ribs extending transversely of the roof E, while H are sections of a reinforcing rib extending longitudinally of the roof, preferably at the center line thereof. As shown, the ribs F are L-shape in cross section and are spaced apart longitudinally of the roof. The upper edges 15 of these ribs F conform in curvature to the curvature of the arch E and are welded thereto while the bases 16 of said ribs are substantially straight. At opposite ends of the roof the bases 20 16 of the ribs F rest upon and are welded to the upper ends of the end wall members C and D, hence it will be apparent that these end ribs F close the spaces at opposite ends of the structure 25 between the roof E and the upper ends of the end wall members C and D.

The rib sections H are preferably between and 30 welded to the transverse ribs F. As shown, these sections H are preferably inverted T-shape in cross section and have opposite ends thereof abutting the vertical webs 20 of the ribs F. The bases 21 of these sections H rest upon and are welded to the bases 16 of the L-shaped ribs F.

As an alternative construction, the ribs F and 35 H may have different cross sections than those described above. For example, either or both of said ribs may be in the form of plain plates such as 30 as illustrated in Figure 7, or either or both may be inverted T-shape in cross section as at 31 in Figure 8, or either or both may be 40 L-shape in cross section as illustrated at 32 in Figure 9. In any instance, the upper edges of the transverse ribs F would conform to the curvature of the roof E, while the longitudinal rib sections H would be between and secured to the transverse ribs F.

45 Thus, from the foregoing it will be observed that our annealing cover is free of gas traps and pockets and permits the gases to pass freely up 50 the upright wall members without any interruption or obstacle. Such cover is comparatively light in weight but is sufficiently rigid and strong to withstand heat and rough handling to which it is subjected while in use. Moreover, our cover 55

may be readily manufactured and assembled at a minimum expense.

What we claim as our invention is:

1. An annealing cover comprising a pair of spaced corrugated upright side wall members of plate metal, a pair of corrugated upright end wall members of plate metal secured to the side wall members at opposite upright edges thereof, an arched roof member of plate metal disposed between the side wall members and secured to the inner faces thereof adjacent their upper edges, opposite ends of said arched roof member extending over and cooperating with the upper ends of said end wall members to provide segmental openings at opposite ends of the structure, and supporting and reenforcing means for the roof member comprising two sets of upright plate-like ribs, one set extending transversely of and being secured to the roof member at spaced points longitudinally thereof, the transverse ribs at opposite ends of the structure extending along and being secured upon the corrugated upper ends of the end wall members whereby such ribs cooperate with the end wall members to support the roof member and cooperate with the end wall members and roof member to close the segmental openings aforesaid, and the second set of ribs extending longitudinally of and secured to the roof member, the ribs of the second set being between and secured also to adjacent faces of the transverse ribs of the first mentioned set.

2. An annealing cover comprising a pair of spaced upright side wall members of plate metal, a pair of upright end wall members of plate metal secured to the side wall members at opposite upright edges thereof, an arched roof member of plate metal disposed between the side wall members and secured to the inner faces thereof adjacent their upper edges, opposite ends of said arched roof member extending over and cooperating with the upper ends of said end wall members to provide segmental openings at opposite ends of the structure, and supporting and reenforcing means for the roof member comprising two sets of upright plate-like ribs, one set extending transversely of the roof member at spaced points longitudinally thereof, the upper edges of said transverse ribs substantially conforming in curvature and being secured to the lower face of said roof member, the transverse ribs at opposite ends of the structure extending along and being secured upon the upper ends of the end wall members whereby such ribs cooperate with the end wall members to support the roof member and cooperate with the end wall members and roof member to close the segmental openings aforesaid, and the second set of ribs extending longitudinally of and secured to the roof member, the ribs of the second set being between and secured also to adjacent faces of the transverse ribs of the first set.

3. An annealing cover having a pair of spaced upright side wall members of plate metal, a pair of upright end wall members of plate metal secured to the side wall members at opposite upright edges thereof, the side wall members being higher than the end wall members and provided throughout substantially their entire area with vertically extending corrugations, an arched roof member of plate metal disposed between the side wall members, opposite ends of said roof member extending over the upper ends of the end wall members and cooperating therewith to provide segmental openings at opposite ends of the structure, opposite side edges of the roof

member being wavy and mating with the vertically extending corrugations of the side wall members, said wavy edges being secured to the inner surfaces of the corrugations of the side wall members below the upper ends of the end wall members, and supporting and reenforcing means for the roof member comprising two sets of upright plate-like ribs, one set extending transversely of the roof member at spaced points longitudinally thereof, the upper edges of said transverse ribs conforming in curvature and being secured to the lower face of said roof member, the transverse ribs at opposite ends of the structure extending along and being secured upon the upper ends of the end wall members whereby such ribs cooperate with the end wall members to support the roof member and cooperate with the end wall members and roof member to close the segmental openings aforesaid, and the second set of ribs extending longitudinally of and secured to the roof member, the ribs of the second set being between and secured also to adjacent faces of the transverse ribs of the first set. 5 10 15 20

4. In an annealing cover, a pair of spaced upright side walls, a pair of end walls secured to said side walls at opposite upright edges thereof, transversely extending vertically disposed plate-like ribs extending along and secured to the upper edges of the end walls, the upper edges of said ribs being arched longitudinally, and an arched roof resting upon and extending longitudinally of the upper edges of the ribs aforesaid, opposite side edges of said roof being between and secured to the inner faces of the side walls adjacent their upper edges, opposite ends of the roof overlapping and secured to the transverse ribs aforesaid, other transversely extending vertically disposed plate-like ribs being between the transverse ribs aforesaid at spaced points longitudinally of the roof, the upper edges of said other ribs conforming in shape and being secured to the lower face of said roof, and longitudinally extending ribs disposed between and secured to the transverse ribs, said longitudinally extending ribs being also secured to the lower face of the roof, portions of the longitudinally extending ribs at opposite ends of the structure extending over the upper edges of the end wall members, and portions of the first mentioned transverse ribs at opposite ends of the structure extending between and secured to said end wall members and longitudinal rib portions just mentioned.

5. An annealing cover having a pair of spaced upright side wall members of plate metal, a pair of upright end wall members of plate metal secured to the side wall members at opposite upright edges thereof, an arched roof member of plate metal disposed between the side wall members and secured to the inner faces thereof adjacent their upper edges, opposite ends of said arched roof member extending over and cooperating with the upper ends of said end wall member to provide segmental openings at opposite ends of the structure, and supporting and reinforcing means for the roof member including two sets of upright plate-like ribs, one set extending transversely of and being secured to the roof member at spaced points longitudinally thereof, the transverse ribs at opposite ends of the structure extending along and being secured upon the upper edges of the end wall members so that such ribs cooperate with the end wall members to support the roof member and cooperate with the roof member and end wall members to close the segmental openings aforesaid, and the second set 71

of ribs extending longitudinally of and secured to the roof member, the ribs of the second set being between and secured also to adjacent faces of the transverse ribs of the first mentioned set, 5 portions of the longitudinally extending ribs at opposite ends of the structure extending over the upper edges of the end wall members, and por-

tions of the transverse ribs at opposite ends of the structure extending between and secured to said end wall members and longitudinally extending portions just mentioned.
